EAR CLIP

Saul Plosky, New York, N. Y.

Application August 29, 1942, Serial No. 456,615

1 Claim. (Cl. 63-14)

This invention pertains to a device which is known as an ear clip for engaging an ear ornament to a person's ear.

An object of the invention is the provision of a device of the indicated character which may be readily slipped on the lobe of the ear in self-clamping engagement therewith and which is prevented from accidentally slipping out of place or off of the ear, but which may be purposely removed from the ear whenever desired by a simple manipulation.

A further object is to provide an ear clip having the aforesaid attributes, which may be used as an ear ornament in itself, or serve as a means for supporting or suspending a separate article of jewelry as an ear ornament of any suitable or preferred kind.

The nature of the invention and its distinguishing features and advantages will appear when the following specification is read in conjunction with the accompanying drawing, in which—

Fig. 1 is a view showing the clip in use;

Fig. 2 is a sectional view, the section being taken approximately on the line 2—2 of Fig. 1 and looking in the direction indicated by the arrows;

Fig. 3 is a sectional view, the section being taken on the line 3—3 of Fig. 4;

Fig. 4 is a side view;

Fig. 5 is a top view;

Fig. 6 is an enlarged sectional view, the section being taken on the line 6—6 of Fig. 3;

Fig. 7 is a view of the ear-clamping member detached;

Fig. 8 is a section of the ear-clamping member taken on the line 8—8 of Fig. 7; and

Fig. 9 is a perspective view of the main part of the clip.

Referring now more particularly to Figs. 3 to 9, inclusive, it will be apparent that the device of the present invention includes a main part 10 which is of U-shape, thereby providing spaced portions 11 and 12, respectively, joined by a connecting portion or bight 13.

In the present instance, the portion 11 is somewhat longer and also narrower than the portion 12. The portion 11 constitutes an ear-engaging member. The portion 12 is relatively wide in order to accommodate an ear-clamping member 14, and is provided with an opening 15 for that purpose. The ear-clamping member 14 is shown most clearly in Figs. 3 and 7. The member 14 in the present instance is preferably in the form of a ring or annulus, to present a

curved periphery which is milled or serrated to provide small projections or ratchet teeth 16. The member 14 has a radially inwardly extending lug and sleeve 17 having a hole 18 therein.

In order to mount the ear-clamping member 14 in functioning position on the main part 10, the portion 11 has transversely aligned bearings 19 near its upper end. The member 14 is disposed in the opening 15 with the lug 17 disposed in registry with the bearings 19. An arbor 20 is supported by the bearings 19 and extends through the hole 18 in the lug 17. In this manner the ear-clamping member 14 is eccentrically mounted on the main part 10 to cooperate with the ear-engaging portion 11 for the purpose of setting up a clamping or gripping action. Resilient means constantly urges the ear-clamping member 14 toward the ear-engaging portion 11. The resilient means in the present instance consists of a coil spring 21 arranged on the sleeve of the lug 17, and one end 22 of the spring bears on the ear-clamping member 14 on the inside thereof, and the other end 23 of the spring is bent around the portion 12 and extends in a groove therein to prevent the displacement of said end 23. The member 14 engages the cross-piece 24 to limit the pivotal movement of the member 14 in one direction under the action of the spring 21.

From the foregoing it will be apparent that there is described a provision and arrangement of parts constituting an ear clip in which an ear-clamping member is supported on the main part of the clip, said main part being of U-shape to provide spaced portions, one of which carries the clamping member while the other itself serves as an ear-engaging member, said ear-clamping member projecting into the space between the upstanding portions of the main part in order to cooperate with the ear-engaging portion to clampingly engage the lobe of the ear to retain the clip on the ear of the wearer. The ear-clamping member 14 presents a curved serrated surface may impinge against and grip the lobe of the ear. The device is one which may be readily slipped on the lobe of the ear in self-clamping engagement therewith, and is prevented, due to the clamping or gripping power of the member 14, from accidentally slipping out of place or off of the ear. In this connection it is to be observed that downward pull on the clip causes the clamping member 14 to impinge with increasing pressure. However, the clip may be purposely removed from the ear whenever desired by simply moving the member

14 against the action of the spring to disengage the same from the lobe of the ear. This may be conveniently accomplished by virtue of any one of the projections 16' which may be engaged by a thumb nail to unclamp the member 14.

It is to be understood that the device may be used for engaging an ear ornament 25 to a person's ear, in which said ornament is suspended from the bight 13 of the part 10, as shown in Figs. 1 and 2, or the ear ornament may be directly affixed to the main part 10. Any ear ornament having a hook or loop may be passed over the portion 11 of the main part 10 so as to hang downwardly from the bight 13 and freely swing thereon.

It is to be understood that the device may be made of precious or base metal, or any other suitable material or combination of materials.

It is to be understood that the invention is not restricted to the precise construction shown, as details of construction may be modified or rearranged in accordance with the invention as set forth in the appended claim.

I claim:

An ear clip comprising a main part formed to

provide spaced portions in continuation of each other, an ear-clamping member projecting through an opening in the first of said spaced portions, said ear-clamping member being in the form of a ring and having a radially inwardly extending lug, an arbor on said first portion extending through said lug to mount the ear-clamping member so as to cooperate with the second of said spaced portions to clampingly engage the lobe of the ear, a spring having the opposite ends thereof in engagement with said first spaced portion and the ear-clamping member respectively, said spring constantly urging the ear-clamping member into cooperative position, and said ear-clamping member being engageable with the ear lobe as the latter is brought between said spaced portions and the ear-clamping member under the influence of the spring thereby clamping said lobe with increasing pressure by reason of any downward pull on the clip, and said ear-clamping member being manipulatable to release said member to remove the clip from the lobe.

SAUL PLOSKY.
